KNITTING MACHINE

Vincent Lombardi, Garden City, N. Y., assignor
to Lombardi Knitting Machine Co., Inc., New
York, N. Y., a corporation of New York

Application December 5, 1936, Serial No. 114,317

59 Claims. (Cl. 66—135)

This invention relates to knitting machines.

An object of the invention is the provision of a knitting machine embodying improved means for embodying an auxiliary yarn into a fabric in such a manner that desirable design effects may be obtained.

A more specific object of the invention is the provision of a knitting machine which is simple in construction, and certain in operation, and whereby an auxiliary yarn may be effectively embodied in a fabric at desired points with a minimum utilization of yarn.

A further object of the invention is the provision of improved means for feeding an auxiliary yarn into position to be received by desired ones of a limited number of needles.

Another object is the provision in a circular knitting machine of simple and compact means for supporting an interior member in such a manner that it will not partake of the relative rotation of the operating means with respect to the needle cylinder.

Other objects of the invention will in part be obvious and will in part appear hereinafter.

The invention accordingly comprises the features of construction, combinations of elements, and arrangement of parts, which will be exemplified in the constructions hereinafter set forth and the scope of the application of which will be indicated in the claims.

For a fuller understanding of the nature and objects of the invention reference should be had to the following detailed description taken in connection with the accompanying drawings, in which:

Figure 1 is a vertical sectional view of one form of machine embodying the invention;

Fig. 2 is a plan view thereof with certain of the parts broken away;

Fig. 3 is an enlarged, fragmentary, top view showing a portion with a sinker bed and one of the supplemental yarn feeds;

Fig. 3a is a fragmentary, vertical sectional view along the line 3a—3a of Fig. 3;

Fig. 4 is an enlarged fragmentary, vertical sectional view showing the supply fingers and the associated mechanism;

Fig. 5 is an enlarged vertical sectional view taken thru the needle bed showing a needle ready for selection;

Fig. 6 is a similar view showing the needle at a later stage in its operation;

Fig. 7 is a similar view showing the needle at a still later stage, and showing a portion of the cam-control mechanism;

Fig. 8 is a perspective view of the parts shown in Fig. 3 taken from the outside of the cylinder;

Fig. 9 is a perspective view of these parts taken from the inside of the cylinder just after a finger has been swung outwardly;

Fig. 10 is a similar view showing the auxiliary yarn caught by the supplemental yarn feed, and the needles in the process of retraction;

Fig. 11 is a similar view showing the auxiliary yarn released by a supplemental yarn feed;

Fig. 12 is a similar view taken at the time of the passage of a main yarn feed and showing one manner of operation;

Fig. 13 is a similar view showing another manner of operation;

Fig. 14 is a view similar to Fig. 9 showing a position of the needles for catching auxiliary yarn into courses wherein the main yarn is knitted so that the auxiliary yarn will appear, at least primarily, on the back of the fabric;

Fig. 14a is a view similar to Figs. 12 and 13 showing the positioning of the needles for the knitting of the main yarn in the portion of the fabric shown in Fig. 14;

Fig. 14b is a perspective view from the inside of the cylinder showing a ribbon fabric as formed by a modified type of operation;

Fig. 15 is a horizontal, sectional view showing the finger-operating means on an enlarged scale;

Fig. 16 is a vertical section on the line 16—16 of Fig. 15;

Fig. 17 is a perspective view of a portion of the cam-operating mechanism;

Fig. 18 is a side view of another portion thereof;

Fig. 19 is a top view of a portion of the mechanism shown in Fig. 18;

Fig. 20 is an end view of the left hand portion of the mechanism of Fig. 17;

Fig. 21 is a somewhat diagrammatic side view of a portion of the machine looking toward the 40 needle cylinder;

Figs. 22-26 are diagrammatic views showing a modified form of operation;

Fig. 27 is a view of the mechanism shown in Fig. 21 as modified to cause the operation disclosed in Figs. 22-26;

Fig. 28 is a view of the rear side of one type of fabric which may be produced by the exemplified machine in accordance with the invention;

Figs. 29-31 are front views of three of the many other types of fabric which may be produced on the exemplified machine in accordance with the invention;

Fig. 32 is a larger front view of another type

of fabric which may be produced in accordance with the invention;

Fig. 33 is a schematic view showing how the mechanism of Fig. 21 may be modified to produce a fabric wherein all of the wales or any desired ones thereof may have design portions in certain parts of the same;

Fig. 34 is a similar view showing the mechanism at a slightly later stage in the operation of the machine;

Fig. 35 is a schematic top view of the mechanism shown in Fig. 33;

Fig. 36 is a perspective detail view showing the construction of one set of the travelers of Figs. 33-35 and the trip mechanism therefor;

Fig. 37 is a similar view showing the construction of the other set of travelers and the trip mechanism therefor; and

Fig. 38 is a view similar to Fig. 1 showing a form of machine embodying a needle dial as well as a needle cylinder.

Ordinarily in the embodiment of an auxiliary yarn into a fabric, as in the formation of stripes, squares, triangles, circles, or other design portions of a yarn of one color or character in a fabric the major portion of which is composed of yarn of another color or character, the yarn is fed to the needles at a point where it is desired to embody it into the fabric, and is carried along each course between these points, either being allowed to hang loose on the back of the fabric or being caught into the fabric in one or another manner. This results in considerable wastage of yarn, particularly when the design portions are widely spaced in the direction of the courses, and also results in undesirably weighting down the fabric with this yarn. By the avoidance of running the yarn continuously along a course these difficulties may be eliminated, and a desirable fabric such, for example, as fabrics of the general type exemplified in my Patent No. 1,589,474, dated June 22, 1926, and a wide variety of other types of design fabrics may be produced in a particularly economical manner. Proposals for the formation of vertically striped fabrics and certain other design fabrics by catching supplemental yarn in individual needles have been made, but such machines are of a highly complicated or otherwise unsatisfactory nature and the number of design effects which can be secured is restricted.

With the foregoing in view the present invention contemplates the provision of a relatively simple and highly effective machine whereby a wide variety of design fabrics may be efficiently and economically produced. In accordance with the invention there may be provided a machine embodying a number of highly desirable features which cooperate in securing the various results desired, but it is to be understood that machines omitting various of such features are nevertheless included within the scope of the invention in various of its broader aspects.

Among such features is the provision of yarn feeds for auxiliary yarn, which yarn feeds form a part of the operating means and rotate therewith when the needle bed is stationary, or are stationary when the needle bed rotates, for example, or which at all events are associated with the operating means so as to partake of the relative movement between the needle bed and the operating mechanism, such auxiliary yarn feeds being arranged to catch and release the yarn at desired points.

Another such feature is the arrangement of

the yarn feeds in a particularly effective manner.

Another such feature is the provision of means whereby a wide variation in pattern effects may be secured.

Another such feature is the provision in a stationary cylinder machine of operating elements whereby the possibility of interference between the various elements is reduced to a minimum.

Another such feature is the provision of means to tie in the rearwardly-extending portion of an auxiliary yarn.

Another such feature is the provision of auxiliary yarn feeds of a character which will exactly dispose a laterally-extending yarn for proper reception.

A further such feature is the provision of improved means whereby supply means for the auxiliary yarn, or other interior member as, for instance, a support for dial needles, may be prevented from partaking of the relative rotation of the operating means with respect to a needle cylinder. In this connection it is to be observed that in circular machines the fabric is ordinarily formed in a tube which hangs down the inside of the cylinder and is withdrawn laterally at the bottom, so that interior members cannot be supported from within the cylinder. Such interior means cannot be supported by lateral arms since the main yarn and the supply means therefor partake of the relative movement of the operating means with respect to the cylinder. The support of such interior means from a central point above the machine provides a cumbersome, and in many instances an impractical structure; and the difficulties in providing a firm support without a great increase in weight and in movability of a machine will be apparent. Proposals have been made for freely supporting such means from a part of the operating means, cooperating lugs on the interior means and on the needle cylinder being provided to prevent the rotation of the interior means. The tube of fabric, however, must pass between these lugs with the result that the portion of the fabric drawn thru the lugs tends to be distorted or worn, the withdrawal of the fabric is made more difficult, and the passage of selvaged edge fabrics, and fabrics having thickened portions, is interfered with. In accordance with the present invention an interior member may be prevented from partaking of relative movement by means carried by the operating means itself, as for instance by gear means associated with the rotating mechanism, with the internal mechanism, and with a part which is normally immovable with respect to the needle cylinder.

Other such features are the provision of variability in the design of the fabric produced by a single machine with a minimum of alterations.

Still other such features will be pointed out hereinafter.

In the form of machine exemplified in Figs. 1-21 there is provided a needle bed which, in the present instance, is in the form of a needle cylinder 5 carried on a stationary framework. About 65 and above this cylinder there extends rotatable operating means including a mounting means 6 which carries a cam ring 7, the operating means being driven in any well-known or suitable manner. Connected with the rotatable mounting 70 means by means of posts 8 and forming a part of the operating means, is a supporting means 9 carrying a rotatable piece 10 on which the usual yarn bobbins 11 are carried. Freely mounted on the supporting means 9 is an interior carrier 75

member 12 on which bobbins 13 for supplemental yarn, and supplying mechanism therefor are carried. An annular rack 14 is mounted on the carrier 12, and an annular rack 15 is freely carried 5 on the mounting means 9 in which are journaled rods 16 at the ends of which are gears 17 and 18 meshing respectively with the racks 14 and 15. The racks are each of the same size and gears 17 and 18 are each of the same size. In order to 10 prevent rotation of the rack 15 with the mounting means 9 there is provided an arm 19 carried on a stationary post 20 and extending into the path of a pin 21 on the rack 15, so that after the pin has contacted with the arm 19 the rack 15 will no longer rotate but will constitute to all intents and purposes a stationary member. Since, 15 therefore, the rods 16 with their gears 17 and 18 are rotating with the mounting means about the axis of the machine the rods will rotate on 20 their own axes due to the meshing of the gears 18 with the rack 15, and due to the latter rotation the gears 17 will cause the rack 14 and the carrier 12 on the one hand, and the mounting means 9, on the other, to have a relative rotation. 25 This relative rotation between the carrier member and the supporting and mounting means 6 and 9 is ordinarily at the same speed as the speed of relative rotation of the latter with respect to the needle cylinder and is in such direction that the carrier member is normally stationary with respect to the needle cylinder. In 30 this manner yarn from the carrier member 12 may be fed to certain needles or groups of needles at any desired time without being carried 35 around the needle cylinder, so as to permit vertical and other striping and other design effects to be incorporated in the fabric in a particularly effective and economical manner. In certain instances it is desirable that the relative position 40 of the carrier member 12 and the needle cylinder be shifted, and to permit this the arm 19 is so mounted on post 20 that it may be shifted so as to alter the position of the carrier member 45 by an amount corresponding to the difference between one or more needles. In the present instance this is accomplished by securing the arm 19 on the rod 20 by means of a set screw 21' and by providing a handle 22 to permit ready shifting of the arm upon release of the set screw. The 50 arm also carries a pointer 23 extending above a dial 24 on the post 20 so that the amount of shifting of the rod can be determined.

The needle bed 5 carries in its slots 25 a series 55 of needles 26 which, as exemplified, are of one of the types disclosed and claimed in my co-pending application, Serial No. 76,754, filed April 28, 1936, being provided at their lower ends with a surface 27 adapted to bear against a portion 28 on the bed to cam the lower ends of the needles laterally when they are moved longitudinally, in the present instance, when they are raised. As exemplified, the needles are of the latch type being formed at their upper end with latches 29, and the needles are held in place by 60 the usual annular spring 30. The bed carries a sinker-carrying member 31, in the slots 32 of which there are disposed sinkers 33 which, with the exceptions hereinafter mentioned, are of the usual type.

70 The actuator mechanism in the present instance comprises a multiplicity of units arranged about the cam ring 1, each unit in the present instance being similar to each of the other units. Each of these units comprises, as will be seen 75 from Fig. 21, a removable and replaceable pattern

wheel 34 held in place by a nut 34a, a raising cam 35, an adjustable supplemental raising cam 36, an adjustable long-butt cam 37, and a stitch cam 38. Each pattern wheel is arranged with suitable selective cuttings and grooves, these ordinarily being different on various of the wheels. The grooves are operative against the butt surfaces 39 on the needles to raise selected needles from a position A to a position B.

As will be seen from Figs. 5 and 6, this movement of the needle results in the lower ends of the needles being thrust laterally due to the camming of the surface 27 against the portion 28, and serves to bring into the path of movement of the succeeding cam 35 the cam-engaging surface 40 of a needle so raised. By means of the cam 35 each selected needle is raised to position C, which is a tucking position in which yarn will be received by the needles without the casting of previously received yarn. When an adjustable cam 36 is in the position shown in dotted (not dot-and-dash) lines in Fig. 21 this cam will form a continuation of the cam 35 and serve to raise the needles to knitting position D. As will be apparent, a Jacquard mechanism or any desired type of selecting means may be utilized in place of the pattern wheels and the cooperating elements shown, to provide for the desired selective actuation of the needles.

Certain of the needles are formed with long-butt portions 41 extending outwardly beyond that edge 42 which runs upwardly from the outer end of the surface 39. Other of the needles are formed without these butt portions, the edge 42 continuing upwardly to provide needles which in effect are short-butt needles. One, two, or more, short-butt needles may be interspersed between spaced ones (or small groups) of the long-butt needles, and the arrangement may be regular or irregular as desired, one form of such arrangement being indicated in Fig. 21 wherein the long-butt portions are blackened. When it is desired to raise to tucking position at a given yarn feed all the long-butt needles which were not selected by the pattern wheel and raised by the cams 35 and 36, the cam 37 will be moved to a position such as shown in full lines at the left-hand side of Fig. 21, whereupon the cam 37 will engage the long butts of the long-butt needles not otherwise raised to raise these needles to the position C. If it is desired to raise to tucking position certain of the needles of only a single group or of successive groups, as for the interlocking in (as disclosed in my Patents 1,541,230 and 1,728,293 hereinafter referred to) of auxiliary yarn instead of knitting the same, the pattern wheel will be provided with suitably spaced grooves at a given portion of its periphery, and both the cams 36 and 37 will be held in a lower position. The stitch cam will retract all advanced needles in the usual manner. The cams 36 and 37 may be adjusted manually or by any suitable mechanism, one form of which is hereinafter exemplified. As will be seen, this arrangement permits any desired type of yarn manipulation to be performed at any particular yarn feed as desired, the cutting of each pattern wheel determining whether or not the cam 35 will be operative to raise any particular needle, the adjustment of the cam 36 being determinative of the extent of the raising, and the cam 37 when raised acting on the long-butt needles regardless of whether or not they have been selected by the pattern wheel. As will be understood, any of various other well known or suitable types of selecting 70 75

and actuating members may be utilized without departing from the invention in its broader aspects.

The machine is provided at points associated with desired ones of the actuator units with yarn feeds 42' of the usual type adapted to feed yarn from the bobbins 11, and at points associated with other of the actuator units with yarn feeds or "travelers" 43 adapted to catch yarn from the bobbins 13 when the same is supplied thereto, and to feed such yarn to a limited number of needles. Each of the yarn feeds 42' is held in position on the member 31 by screws 42a, and each of the travelers 43 is held in place thereon by screws 43a, the member 31 being provided with suitable screw holes (not shown) at suitably spaced points around the machine, so that either a main-yarn feed 42' or a traveler 43 may be provided in association with any desired one of the actuator units. This permits wide adaptability of design, and permits the utilization of the machine for the production of a large number of types of fabric.

In order to supply yarn to the yarn feeds 43 there are provided yarn supply fingers 44 which are carried in suitable ones of slots 32 in the carrier 12 and are pivotally mounted on annular ring 45 (Fig. 4) fitting in notches 46 in the fingers 44; an annular spring 46a fitting into an annular slot 46b in the carrier 12 being provided to support them. As exemplified, these fingers 44 are arranged in groups, each finger of a group being adapted to supply a yarn of a different color or character so that design figures of different colors may be made to appear at different points in the fabric,—each group being composed of three fingers in the present instance. It will be appreciated, however, that a single finger may be utilized instead of a group of fingers in instances where a design figure or figures in a given number of wales is to be of only one color and character. Auxiliary yarn extends to the thread hole 47 in each finger thru an eyelet 48, over a guide 49, thru an eyelet 50, and over a sheave 51, to the respective bobbin 13 for the finger. Each group of fingers (or single finger) is disposed somewhat at the rear (in the direction of rotation of the operating mechanism) of the particular needles by which the auxiliary yarn is to be knit. Each finger is normally maintained in the positions shown in full lines in Fig. 4, by means of a spring 52, but is adapted to be swung by pressure on its upper end to a position such as shown in the dot-and-dash lines.

Each of the supplemental-yarn feeds or "travelers" 43 is provided with a pin 53 which is adapted to catch yarn held in front of the traveler, and, as will be seen from Fig. 9, the swinging of a finger from an inward to an outward position will position the yarn so that it will extend in front of the traveler and will be caught by the pin. Each of the travelers has an upwardly sloping surface portion 43b serving to lift the laterally extending auxiliary yarn positioned by a finger, thus moving this yarn in a direction transverse to the direction in which it extends—so as to properly dispose it in the desired position for reception by the needles upon its being caught by the pin 53 and fed to the needles. By a construction of this type the fingers, or other means which cause the yarn to extend laterally, can be so arranged as to be most effective and to collaborate best with the other parts of the machine, and do not themselves need to exactly dispose the yarn for proper reception by the needles.

Moreover, the yarn will be fed to all of a plurality of needles in exactly the same position. The rounding of the traveler also assures against catching of the yarn before the pin reaches it. Each traveler 43 is associated with one of the actuator units so that all or certain of a group of needles (as selected by the pattern wheel or by such other selector member or mechanism as may be employed) may be raised to a desired point for reception of yarn from the traveler. The traveler will serve to feed the yarn to the needles in the manner, for example, as illustrated in Fig. 10. As will be seen, therefore, the projection of the needles will not be operative to embody an auxiliary yarn into the fabric except at such times as a finger is swung outwardly, nor will the swinging of a finger outwardly feed yarn to any needles unless certain of the needles are advanced by the actuator unit. The pin 53 is retractably mounted on the traveler, and there is provided a trip member 54 pivoted at 55 (Fig. 8) and carrying at its rear end a rod 56 connected to the pin (Fig. 3a) so as to retract the pin when the forward end of the trip member 54 is raised, the pin being normally held projected by means of a spring 57 acting on the forward end of the trip member. Thus the pin will continue to draw out the yarn until the trip member 54 is tripped. In order to trip the member 54 there are provided in the slots 32 of the sinker-carrying member 31, at points suitably in advance of those groups of needles which are to manipulate the yarn to provide design effects in particular wales, special sinkers 33a each of which has a raised rearward portion 58 which will act on the sloping surface 59 of the trip member to actuate the trip member and retract the pin, thus releasing the yarn; those needles which received the yarn having, in the meantime, been retracted by the stitch cam of the actuator unit associated with the traveler. The sinkers 33 and the special sinkers 33a are removably carried in the slots 32 in the usual manner, so that the special sinkers may be set at the proper point for the production of any particular fabric which it is desired to produce. In order to retighten the yarn as soon as it has been released by the pin and to hold it taut during its manipulation, the guide 49 is supported from a resilient wire 60 which tends continuously to draw it upwardly to the positions shown in dot-and-dash lines in Fig. 4. As will be understood, it is not necessary that the fingers swing from a point within the cylinders outwardly in the manner exemplified, but they may, in certain instances, be arranged to swing from an outward, upward, or any other desired point, to a point wherein they will position the yarn so that it will be caught by the traveler, suitable guide means such as 48, 49, and 50 being provided at whatever point may be most desirable.

In the type of construction exemplified in Figs. 9-11, and 21 the pattern wheel associated with a traveler will select a plurality of needles, in the present instance five; the cams 35 and 36 will advance these needles to knitting position D; the finger 44 will be swung outwardly, as shown in Fig. 9; the pin 53 of the traveler will catch the yarn and feed it to any selected needles above their latches; the needles will be retracted by the stitch cam; and the trip mechanism will operate to release the yarn; whereupon the finger may be swung inwardly so as to be out of the way of a yarn carrier 42' when the latter passes. The number of needles by which it is possible to knit a supplemental yarn may be varied by varying 75

the position of the special sinker 33a, and the position of this may be varied considerably depending on the extent of the design portions desired, the capacity of the machine, the ability 5 of the traveler to feed yarn to a given number of needles, the spacing of the travelers and the main yarn feeds, the take-up ability of the spring 60, and various other factors; as many as sixty or more needles being utilizable in certain 10 instances, as when the various yarn feeders are well spaced. On the other hand, if the knitting or catching of an auxiliary yarn in only one wale is desired, as in making a vertical stripe, or in knitting single loops in spaced courses in the 15 same wale, the special sinker may be set to release the yarn almost as soon as it is caught, so that the traveler will tend to feed it only to the one needle which is raised. Depending upon the selection by the pattern wheel, any given one or 20 ones of such of the needles as are utilizable to receive yarn from a given finger may be caused to knit at any desired course, thus enabling zigzag, triangular, curved, or other irregular effects to be readily produced as desired. The 25 needles which knit may be spaced, if desired, so as to cause two adjacent design figures, or two adjacent but separated parts of a single design figure, to be formed. Furthermore, when desired, the pattern wheel may be caused to select 30 only spaced ones of the needles which are adapted for the reception of a yarn from the traveler, and the cams may be adjusted, as for instance by the means hereinafter disclosed, so that the cam 36 will be in inoperative position, so that the 35 desired ones of the needles (whether long-butt or short-butt needles) as selected by the pattern wheel will be in tucking position, as for example when it is not desired that the auxiliary yarn appear on the front of the fabric, but only on 40 the back, as in Figs. 14 and 14a. In this case the primary yarn would be knitted at the places where the auxiliary yarn is caught in.

Those needles which are not operated to receive supplemental yarn from the traveler yarn feed 45 will ordinarily be operated to receive yarn from the main-yarn feed. They may, for instance, be operated by an actuating unit such as shown at the left hand side of Fig. 21 to receive and knit yarn from a yarn feed intermediate the travelers 50 in the manner shown in Figs. 12 and 13, or they may be caused to knit yarn from one main-yarn feed and the cam 37 or other means caused to operate alternate or otherwise spaced needles merely to catch a yarn into a fabric at one or more 55 other main-yarn feeds, these main-yarn feeds, for instance, being arranged in succession without there being any traveler (or, at any rate, any operative traveler) interposed, and, if desired, the selecting means being arranged to cause different needles to knit at different main-yarn feeds,—so as to produce a fabric wherein two main yarns are so embodied in the fabric as to themselves produce designs, with one or another of the main yarns "interlocked" or caught into 60 the fabric in the certain of the manners exemplified in my Patents 1,541,230 and 1,728,293, for example, or in other manners disclosed in these and others of my patents, or otherwise known to those skilled in the art. In the latter case either or 65 both of the yarns at the main-yarn feeds may (for the purposes explained below) be caught into portions of the fabric where the auxiliary yarn is knitted. The removability and replaceability of all the yarn feeds and the provision of 70 similar actuating units at each yarn feed in the

exemplified construction, permits any number of main-yarn feeds to be arranged in succession without reducing the total number of operating yarn feeds on the machine, so that a compact, readily adaptable construction is provided. 5

When there is employed a zigzag, diagonal, diamond-shaped, triangular, or other construction wherein the loops of the main yarn and the loops of the auxiliary yarn overlap in successive rows and are accordingly interknitted, the main yarn 10 (or some or all the main yarns, as in the case when two main yarns are arranged in interlocking formation) may either be caught into the portions of the fabric where the auxiliary yarn is knitted or may be carried loosely in back of the 15 fabric over such portions, as shown in Fig. 13 wherein the loops of auxiliary yarn are shown darker than the loops of primary yarn. In this construction the lines of loops of auxiliary yarn are staggered so that the end-loops thereof are 20 interknitted with the end-loops of the primary yarn, different end-needles being operated for the knitting of the two yarns in successive rows,—the cutting and arrangement of the pattern wheels being suitably modified to this end. When, however, the edges of a portion of auxiliary yarn are 25 vertical (as in Figs. 9-12), it is necessary that the yarn knitted in different portions be tied together in some way, and to this end spaced ones (1, 3, and 5 in the present instance) of the (five) 30 needles which perform the knitting of the auxiliary yarn (as in Figs. 9-11) and which are not advanced to knit at the main yarn feed (as in Fig. 12), will act to catch the main yarn without knitting, so as to firmly hold the different portions of 35 the fabric together. To this end the long-butt needles which are not otherwise advanced are advanced to position C at the main-yarn feed by the cam 37 of its actuating unit, this cam 37 being held in advanced position for this purpose. It is 40 to be understood in this connection that it is possible to advance all the needles at the main-yarn feed to position D to interknit loops with the loops of the auxiliary yarn, so as to form a double row of loops at the portions where the auxiliary 45 yarn is knitted; and that it is also possible to cause a main yarn to be knit in every other course and an auxiliary yarn to be knit in every other course in a desired portion of the fabric, so that in the design portion the loops of the 50 main yarn will be replaced by loops of auxiliary yarn only in alternate (or otherwise spaced) courses,—the pattern wheels and cams being suitably formed and arranged for such purposes. If desired also, the pattern wheel formation, or the 55 arrangement of whatever other selective means may be utilized, may be such as to cause the needles to catch the auxiliary yarn into certain portions of the fabric without knitting so that the auxiliary yarn will appear primarily, at least, on 60 the back of the fabric. In Figs. 14 and 14a there is shown an arrangement of this type wherein certain spaced needles at one portion of the bed are partially advanced (to position C) to receive auxiliary yarn from one of the travelers without 65 knitting so as to catch this yarn into the fabric in courses wherein the main yarn is knitted, the pattern wheel associated with the traveler being suitably formed for this purpose, and the cam 36 70 thereat being in a lower position so as to be inoperative; and the pattern wheels at the main-yarn feeds being arranged to fully advance (to position D) all the needles at this portion and the cams 36 thereat being in advanced position.

There are many instances in which it is de- 75

sirable to use a circular machine to perform special jobs, such as the production of ribbon fabric; and by means of the present invention this can be readily done. In the present instance 5 this may be accomplished by disconnecting the yarn supply of the main-yarn feeds, by omission of the pattern wheels, or by substituting travelers for the main-yarn feeds and making any other necessary adjustments in the machine, where- 10 upon the machine will operate as indicated in Fig. 14b to produce one or more unconnected ribbons of fabric. In this manner a single machine, which is ordinarily used to produce tubular design fabric, may, when necessary, be used instead of 15 a multiplicity of ribbon machines.

As may be seen from Figs. 1 and 2, the carrier 12 is slotted thruout its periphery as indicated at 16 61, so that fingers such as 44 may be provided at any desired point, thus providing for the maximum 20 flexibility in operating characteristics. As will also be seen, the three fingers 44, which are provided in each group in the particular arrangement exemplified, are provided with differently constructed upper ends providing surfaces 62, 63, and 64 on different levels. In order 25 to control the operation of the fingers in connection with the passage of such travelers as are being utilized, there is provided in association with each traveler an actuating unit 65 comprising 30 plunger cams 66, 67, and 68 disposed on planes such that they will contact the surfaces 62, 63, and 64, respectively. The finger-actuating units 65 are carried on the posts 8 forming a part of the operating mechanism and extending, in the present instance, between the mounting means 6 and the supporting means 9. As 35 will be seen from Figs. 2 and 4, when a plunger cam is advanced it will bear against the surface alined therewith on a particular finger in each group of fingers and push the upper end of that finger rearwardly to swing the finger outwardly. As soon as the plunger cam has passed, however, the spring 52 associated with the finger will tend 40 to swing it inwardly again. In this manner the fingers are selected for operation at such times as it is desired to have the supplemental yarn embodied in the fabric in the form of a design, the particular finger of a group to be operated at any particular time is selected, and the operation 45 is so controlled as to swing the finger at the proper times in connection with the operation of the mechanism as a whole.

In order that the operation of the plunger cams may be controlled, each of them is formed with 50 a slot 69 (Figs. 4, 15, and 16), thru the forward end of which a post 70 mounted on the framework 71 of the unit 65 extends. The plunger cam is held in rearward (outward) position by means of a spring 72. A second post 73 extending thru slots 74 serves to hold the plunger cams firmly in place. Each of the cams is provided with a pair of rounded notches 75 and 76 adapted to receive a pin 77 on a catch member 78 which is pivotally mounted at 79 on the framework 65 71; the catch member normally being held in the position shown by the full and dotted lines by a spring 80. When a plunger cam is moved forwardly against the pressure of the spring 72 the catch member 78 will be swung by the camming action from the edge of the notch 75 to the position shown in dot-and-dash lines in Fig. 15, from which it will be pulled back by the spring 80 so that the pin will enter the slot 76 so as to hold the plunger cam in forward position. When 75 it is desired to release the plunger cam the catch

member 78 will be swung outwardly to draw the pin out of the notch 76, whereupon the spring 72 will push the plunger cam back into rearward position and the pin 77 will reenter the notch 75. To control the operation of the plunger cams and of the catch member 78 there is provided a control cam 81 (Figs. 1 and 15) carried on a stationary rod 82 which is movable between four positions so as to place the cam 81 in position to contact the rearward end of any one 10 of the three plunger cams or of the catch member 78, as desired. Thus by properly positioning the rod 82 any one plunger cam may be moved forwardly at a given period in the operation of the machine, or a plunger cam which is forward may be allowed to spring rearwardly by operation of the catch member or the operation of another member. The operation of the rod 82 may be controlled by any desired type of pattern-control mechanism, such for instance as 20 the pattern chain 83 exemplified in Fig. 1, this chain being provided at various points with nubs 84, 85, and 86 of different heights and with portions 87 without nubs. The nubs are adapted to bear on a lever 88 and connected with the rod 25 82 at 89, the lever being normally held downwardly by a spring 90.

In instances where the body of the fabric is to be composed of two primary yarns, one of which is knitted in one portion of the fabric and another of which is to be knitted in another portion of the fabric, as for instance in the production of a two-color interlocked fabric, or other similar fabrics, as disclosed in my said Patents 1,541,230, and 1,728,293, two main-yarn feeds 42' 35 may be disposed in succession and the pattern wheels thereat cut in a complementary or other suitable fashion. In this instance, and also in instances where the operation at the main-yarn feed is of a character indicated in Fig. 12, it is 40 desirable that both of the cams 36 and 37 which are associated therewith be in advanced positions at the same time; whereas in other instances, as at the supplemental-yarn feed, and in instances where primary yarn is not interlocked with primary yarn in a design fashion, and where the needles are operated in the manner indicated in Fig. 13, it is desirable that only the cam 36 be raised. Accordingly, there is provided, as exemplified in Figs. 7, and 17-20, a 50 form of mechanism embodying a specific feature of the invention, but which, as will be understood, may be replaced by other well known or suitable mechanism for obtaining the same or other types of cam operation. In the embodiment exemplified there is provided a shifting sleeve 91 which is affixed by means of a screw 92 to a rod 93 on the end of which the cam 36 is carried. A partial rotation of the sleeve 91 will accordingly serve to raise or lower the 55 cam 36 depending upon the direction of rotation. The cam 37 is carried on the end of a sleeve 94 which extends about the rod 93 and inside the inner end of the sleeve 91. If it is desired to raise the cam 37 at the same time 60 as the cam 36 a screw 95 extending thru the sleeve 91 is screwed downwardly to bear against the sleeve 94. In order to prevent the friction of the rod 93 against the inside of the sleeve 94 from moving the cam 37 when the screw 95 is 65 not screwed down, there is provided a screw 96 extending thru a tube member 106 which projects from the cam ring 7. Accordingly, in operation, either the screw 95 or the screw 96 will be screwed down, the other being screwed up so 70 75

as to be inoperative. In order to impart partial rotations of the sleeve 91 at desired stages in the operation, each sleeve 91 is provided with a trip member 98, and there is provided on a stationary arm 100 a trip plunger 101 which is adapted to be projected into the path of trip member 98 so that when the trip member passes it will be lifted in the direction of the arrow in Fig. 20 from the position shown in dotted lines in Fig. 17 and in full lines in Fig. 20 to the position shown in full lines in Fig. 17 and in dotted lines in Fig. 20, where it will be held against further movement by a surface 102 on a catch member 103. The catch member is pivotally mounted on a rod 104 carried on arm 105 on member 106 which is affixed to the mounting means. The sleeve 91 is normally held in position, with the trip member 98 downwardly, by means of a spring 107 secured to the member 106 at 108. A spring 109 serves to draw the catch member 103 toward the sleeve 91. The sleeve 91 carries a lug 110 which, when the trip member 98 is in upper position will bear against a shoulder 111 on the catch member 103. In order to permit the return of the trip member 98 and the sleeve 91 to the position wherein the trip member is down, the catch member is pushed outwardly as for instance by a trip plunger 112 which is projectable into the path of an arm 112a on the catch member 103. A shoulder 112b on the catch member serves to limit the downward movement of the trip member 98. Thus by the projection of one or the other of the trip plungers 101 and 112 the position of the sleeve 91 is controlled.

In order to provide a pattern control for the operation of the trip plungers 101 and 112 there is provided in the present instance mechanism including a connecting member 113 which is pivoted at 114 and to which the rear ends of the trip plungers are pivotally connected at 115 and 116. On the rear end of the member 113 there is pivoted at 117 a link 118 which is drawn downwardly by a spring 119 and is pivoted at 120 to an arm 121 which is pivoted at 122. The arm 121 carries a projection 122' which is adapted to rest upon one or another of either the pins 123 of a lower series or the pins 124 of an upper series on a ratchet wheel 125, one surface of the projection 122' being curved, so that the projection will rise up on a pin 124. Thus the position of the member 113 will be determined by which of the pins 123 and 124 the projection 122' rests on. A spring-pressed pawl 126 pivoted at 127 on a link 128 serves to cooperate with the teeth 129 of the ratchet wheel to hold this wheel in position and to advance the wheel one step at a time at one or more points in each revolution of the operating means. This is accomplished thru the medium of a cam portion 130 on a part 131 carried by the mounting means 6. This cam portion serves to project a roller 132 carried by a link 133 so as to swing the link on a pivot 134 against the pull of a spring 135. The link 133 is pivoted at 136 to a link 137 which is pivoted to a vertical arm 138 and fixedly connected by screws 139 to the link 128, which is supported and guided at 140. The pawl 141 serves to prevent the ratchet wheel from being drawn back by the pawl 126.

In many instances it is permissible to allow that portion of the auxiliary yarn which is adjacent to a portion which has just been knitted to lie loosely against the back of the fabric as shown in Figs. 9, 10, and 11. In other instances, however, it is

desirable that this be caught into the body of knitted yarn at one or more desired points. This may be readily accomplished in a machine of the character exemplified by causing certain, for instance alternate, ones of the needles, which have 5 knit the auxiliary yarn as it is drawn out, to be positioned for the reception of this yarn without knitting, as it extends rearwardly after the knitting operation thereof has been completed,—for instance certain spaced ones of a group of latch needles may be advanced to tucking position at 10 this stage. For example, as shown in Figs. 22-26, a group of five needles may be advanced to receive yarn from a traveler 43 which has caught 15 yarn from a finger 44, and be retracted to knit 20 the yarn. Fig. 22 shows the members at substantially the same stage as they are shown at Fig. 10, and Fig. 23 shows the needles retracted. Before 25 or after the release of the yarn from the pin 53 on the traveler 43 in the manner brought out above, the second and fourth needles of the group are advanced to tucking position as shown in Fig. 24. While the needles are in this position, the release of the finger 44 from its plunger cam in a unit 65 occurs, so that the finger will swing rearwardly thus drawing the yarn against the advanced needles as indicated in Fig. 25, the rearward position of the finger 44 being indicated by its showing in dotted lines. Thereupon the 30 needles may be retracted as indicated in Fig. 26. The advance and retraction of the second and fourth needles of the group may be caused by any suitable means, such means being exemplified in Fig. 27, and comprising a pattern wheel 142 similar to the pattern wheels 35, a cam 143 which is 35 adapted to raise the needles selected by the pattern wheels to the position C in the same manner as the cam 36, and a cam 144 which is operative after the passage of the finger-actuating unit 65 to retract the advanced needles. 40

In Figs. 28-31 there are shown a few of the large variety of designs which can be produced on the above described machine in accordance with the invention.

Fig. 28 is a rear view of a form of fabric embodying several designs. The portions where the primary yarn, which may be a white yarn, is knitted are shown at 200. At 201 there is shown a vertical stripe of auxiliary yarn, which may be green, which stripe is of the character shown in 50 the process of formation in Figs. 9-11, the main yarn being interlocked in this portion by an operation such as shown at Fig. 12. At 202 there is shown a laterally spaced portion of the fabric wherein two auxiliary yarns are knitted to produce successive diamonds. For instance, the first finger of a group of fingers will be operated to project a red yarn 203 at each of several successive courses; and another finger, for instance the second finger of a group, will be operated to project a blue yarn 204 for several immediately following courses; after which the first finger will again be operated for several more courses; and so on. As will be seen from the drawings, the portion of one yarn which extends vertically between the parts of the fabric wherein it is knit will lie over the horizontally extending floats of the other yarn and will serve to hold these floats against the body of the fabric. In general, long 60 loose return yarns may be held by short vertical 65 yarns on the back of the fabric. In the production of these diamonds, as will be understood, the cuttings of those pattern wheels which are associated with successive travelers will be such that an increasing number of needles and then a de- 70 75

- creasing number of needles will be advanced at successive ones of the auxiliary yarn feeds. As above indicated, while diamonds are being formed of the red yarn 203 the blue yarn will be carried 5 at the back of the fabric and will extend vertically as shown at 205, and while the blue yarn is being knitted the red yarn will be at the back of the fabric and will extend vertically as shown at 206.
- 10 Fig. 29 shows the front of a fabric in which triangular designs 208 of auxiliary yarn are provided in a fabric, the main yarn of which is interknitted at 209. In the production of this fabric the cutting of the pattern wheels associated with 15 successive travelers is such as to advance an increasing number of needles thruout several courses and then to advance no needles thruout several more, the pattern wheels associated with the main-yarn feeds being arranged so as not to advance the needles advanced by the pattern wheels 20 of preceding auxiliary-yarn units, but to advance all the needles during the courses indicated at 210, wherein the preceding pattern wheels do not advance any of the needles.
- 25 In Fig. 30 there is shown a design effect produced by including a number of differently colored yarns in a fabric, the body of which is white yarn. For instance, a triangular design of black yarn 211 is produced by swinging the first of one 30 group of fingers outwardly, portions of red yarn 212 are produced by swinging outwardly the second of the fingers of this group, and the portions of blue yarn 213 are produced by swinging outwardly the third of the fingers of this group; 35 while portions 214 of black yarn are formed by swinging outwardly the first of the fingers of another group, portions 215 of brown yarn are produced by swinging outwardly the second of the fingers of the second group, and portions 216 of 40 yellow yarn are produced by swinging outwardly the third of the fingers of the second group; the pattern wheels being cut to provide for the proper knitting-in as shown.
- In Fig. 31 there is shown a zigzag stripe 217 45 which may be of heavy wool whereas the primary yarn is rayon. This zigzag stripe may be produced by having cuttings on those pattern wheels which are associated with successive travelers so that the following needles will be raised in successive courses: 1—7, 2—8, 3—9, 4—10, 5—11, 50 6—12, 7—13, 6—12, 5—11, 4—10, 3—9, 2—8, 1—7, 2—8, etc.
- 55 It will be appreciated that the foregoing discussion of the particular needles to be raised is merely illustrative of the type of actuation which may be obtained in accordance with the invention, and it is not intended to imply that the particular pattern wheels specifically illustrated are cut to produce any particular one of these designs.
- 60 It will be appreciated that machines such as contemplated by the invention may be constructed to produce fabrics wherein design portions appear in some part of every wale, the invention in its broader aspects not being limited 65 to machines wherein design portions appear only in certain wales although the invention may find its most frequent use in the latter type of machine. In Fig. 32 there is exemplified a fabric wherein the design portion 218 is in the form of diagonal stripes which cross each other, the design portion, for instance, being composed of red yarn while the remainder of the fabric 219 is composed of white yarn.
- 70 In Figs. 33—37 there is shown an embodiment 75 of the invention whereby design portions may be
- knitted in part of each wale of the fabric. In the present instance the selective means used are pattern wheels so cut as to cause striping running diagonally in one direction to be embodied in the entire fabric. It will be appreciated, however, that by the use, in accordance with the invention, of suitable mechanism for feeding and embodying into the fabric the auxiliary yarn, and of selecting means, as for instance pattern wheels with suitable cuttings, or pattern-controlled Jacquard mechanism of suitable types, fabrics such as exemplified in Fig. 32 or fabrics containing any other desired type of design formation with the design portions appearing thruout different portions of all of the various wales may be produced. In the particular form of the invention here exemplified the various parts are similar to the parts previously exemplified, except as hereinafter indicated, and the corresponding parts, except where otherwise specifically designated, are designated by similar reference numerals with the subscript c.
- In the present instance there are provided, instead of a single set of travelers each of which is tripped at predetermined points thruout the machine, a plurality of sets of travelers, (two, as exemplified) the travelers of one set being adapted to be tripped at certain points and the travelers of the other set being adapted to be tripped at certain other points, and certain fingers are 30 adapted to be operated for supplying yarn to one set of travelers and other fingers for supplying yarn to the other set of travelers, separate plunger cams being provided for the different sets of fingers. In order to readily understand the construction and operation, the bank of needles and the fabric produced thereby should be considered as divided into zones, the needles in zones E being controlled to knit yarn from one set of fingers, and the needles in the alternate 35 zones F being controlled to receive yarn from the other set of fingers. While the zones as illustrated are divided by straight lines for the sake of simplicity, it should be understood that in ordinary practice adjacent zones will not be separated by straight lines, but that the rows of 40 knitted yarn will meet first on one side and then on the other side of the median line between the zones, so as to insure sufficient overlapping between one end of a row in one zone and the other end of a succeeding row in the other zone,—for example as shown at Q in Fig. 33,—so that the two zones will be securely interknitted in the form of a continuous fabric. It will be appreciated that each traveler feeds the yarn in a position 45 to be received by needles a sufficient distance to each side of the median division line of the zones to permit this overlapping. In cases, however, where the portion of the fabric in the different zones is held securely together by other means, 50 as where the main yarn is caught into the fabric as by interlocking thruout the pattern areas, as in Figs. 9—12, the division line between the zones may be a straight line. There are provided separate actuating units for controlling the needles 55 for the reception of auxiliary yarn from each of the two sets of fingers, as well as actuating units for controlling the reception of primary yarn from the main-yarn feeds. In the present construction each actuating unit comprises a pattern wheel 34c arranged similarly to the pattern wheel 34, but, of course, specially cut. The pattern wheels 34c shown at G and H, which are adapted to select the needles for receiving auxiliary yarn, are entirely slotted so as to be inop- 60

erative thruout certain portions (half) of their extent, as indicated on the complementary half-sections F and E on the pattern wheels G and H respectively. The other half-sections of these 5 wheels,—i. e., the portion E of the wheel G, and the portion F of the wheel H,—are formed with design cuttings so as to advance selected needles in the zones E in the case of the pattern wheel at G, and in the zones F in the case of the 10 pattern wheel at H. The two half-sections thus have a selecting action equivalent to that of a single pattern wheel. Each successive pair of pattern wheels, in the present instance, will have their cuttings modified that the grooved portions 15 will be arranged to select groupings of needles one needle to one side of those selected by the grooved portions of the preceding pair so that the wales in which the auxiliary yarn is knitted will be such as to produce the diagonal striping indicated in 20 Figs. 33 and 34, it being appreciated that in the particular construction exemplified there may be as many pattern wheels G and H as there are needles in each of the zones E and F respectively. The pattern wheels at I are arranged to control 25 the needles for the knitting of the primary yarn and are cut so as to have slotted portions in a section E corresponding to the grooved portions in the section E of the preceding pattern wheel G and slotted portions in section F correspond- 30 ing to the grooved portions in the preceding pattern wheel H, the remaining parts of the peripheral pattern wheel I being grooved portions. Thus the pattern wheel G will serve to advance among others the needles indicated at J and K in 35 the central zone E of Fig. 33 for knitting auxiliary yarns in portions of a course as indicated at L and M respectively, and the pattern wheel H will advance the needles as indicated at N in the central zone F of Fig. 33 to produce the de- 40 sign portion O in the same course, it being noted that the portions L and O are juxtaposed so as to provide a continuous lateral portion of the diagonal stripe including these portions. By the provision of such a construction, as will be seen, 45 it is unnecessary that a single auxiliary yarn be drawn past the needles at J and N for the production of the design knitting L—O, but one auxiliary yarn 220 may be knitted to provide the portion L (as well as the portion M) and another auxili- 50 ary yarn 221 (preferably of the same color and character as the yarn 220) may be knitted to provide the portion O. Thus the distance thru which a single auxiliary yarn needs to be drawn out is limited to a distance not materially greater 55 than a given zone; whereas design figures extending without break from one zone to another zone may be readily provided.

A finger 44E of a set of alternately disposed fingers corresponding to the zones E will be 60 swung out by the plunger cam 65G prior to the passage of the pattern wheel at G so that its yarn 220 will be received by a traveler 43G to be fed to those needles in a zone E which are selected by a pattern wheel at G, and the fingers 65 44F of another set will be swung out (by a plunger cam 65H) to supply yarn to travelers 43H for feeding yarn to those needles in a zone F which are selected by a pattern wheel at H. The travelers 43G are provided with trip members 70 59G, which are disposed in one lateral position; and there are provided on certain of the sinkers 33c disposed at 33E trip portions 222 arranged to trip the trip members 59G on travelers 43G. The travelers 43H are formed with trip members 75 59H positioned differently from the trip mem-

bers 59G and arranged to be tripped by trip portions 223 on those of the sinkers 33c which are disposed at 33F. It is to be particularly noted that the portions 222 will not contact with the trip members 59H and will accordingly not trip the travelers 43H, and that the portions 223 will not contact with the trip members 59G and will accordingly not trip the travelers 43G. Thus alternate travelers will receive yarn supplied by the fingers 43E and will feed this yarn to the 10 needles in the zone E and will be tripped after this feeding operation is completed; whereas the intermediate travelers will receive yarn from the fingers 43F and will feed yarn for reception by the needles in zones F and will thereupon be 15 tripped,—the selective means, exemplified by the pattern wheels, being so arranged that no needles will be advanced adjacent to the points where any traveler receives or releases yarn, and the plunger cams being so arranged that the fingers will be advanced for supplying a yarn to a traveler only when a traveler of a given one of the sets is about to pass. As will be noted, the outwardly swung fingers are indicated in full 20 lines, and the retracted fingers indicated in dotted 25 lines. The particular machine exemplified is a large machine having a large number of yarn feeds; but it will be appreciated that by a suitable arrangement of the selecting means (as by the use of larger pattern wheels with suitable 30 cuttings) or the use of a particular type of selecting means arranged to give desired needle movements at desired points in any of a number of well known ways, (as by the use of Jacquard mechanism) the present feature of the invention may be embodied in any of a wide variety 35 of types of machines.

As above indicated, a needle dial may be supported interiorly of a needle cylinder in accordance with the invention; and, as will be appreciated, machines for the formation of striping or other design effects in accordance with the invention may embody both cylinder and dial needles, such as utilized for example in the production of rib-knit fabric, as well as machines employing only one set of needles. In Fig. 38 there is exemplified a form of machine embodying both cylinder and dial needles, the latter in the present instance being supported interiorly of the cylinder in accordance with one feature 60 of the invention.

In the form exemplified there is provided a machine which is similar in most respects to a machine exemplified in Figs. 1-21, and wherein the similar parts are designated by similar reference numerals. In the present instance, however, the interior carrier member and its associated parts are modified. The carrier member shown at 12d comprises a supporting plate 300 carried from the cylindrical portion 301 of the 60 carrier member by means of brackets 302. The plate 300 carries bobbins 13 for the auxiliary yarn, and guide means similar to the guide means carried by the carrier 12. The plate 300 also supports a dial 303 on which there are carried a 65 series of dial needles 304 which are generally similar to the cylinder needles 26, the portion of the dial at 305 being formed similarly to the portion of the cylinder at 28. Supported on an annulus 306 are actuating units, each comprising a cam 307 which is the equivalent of the cams 35 and 36 taken together; and a stitch cam 308. The annulus 306 is freely supported on the plate 300, as indicated at 310. In order to provide for the rotation of the annulus 306 with 70 75

respect to the dial 303 there is provided gear means similar to the gear means which provides the relative rotation between the carrier member and its supporting means, this gear means consisting, in the present instance, of an annular rack 320 on the annulus 306, a similar rack 321 on a cylindrical member 322 depending on the member 9, and a pair of mutually similar gears 323 and 324 meshing respectively with the racks 320 and 321 and fixed on a shaft 325 which is rotatably carried by the part 301 of the carrier 12d. Thus; just as the gears 17 and 18 and the associated mechanism provide means for causing relative rotation between the carrier 12 (and the carrier 12d) and the mounting means which is intermediate the interior carrier and an exterior member such as the posts 20, the posts and the means 9 being relatively rotatable; the gears 323 and 324 and associated mechanism provide means for causing relative rotation between the carrier 12d, which is an intermediate member, and the dial and the exterior means 9 from which the carrier is supported.

The term "course" as used in the appended claims is to be understood as describing a course of the cams or other operating means past a series of needles, or of a series of needles past the cams or other operating means, as for example in a complete rotation of the cam ring, or the needle bed, of a circular knitting machine, and is not to be considered as limited to the formation of a row of loops in the fabric or any particular portion thereof unless specifically so defined in a particular instance.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

I claim:

1. A knitting machine comprising a needle bed, operating means, said bed and said operating means being mounted for relative movement, a series of needles on said bed, means forming part of said operating means to feed primary yarn into position to be received by said needles, auxiliary-yarn feeding means forming part of said operating means, movable means comprising at least a part of said auxiliary-yarn feeding means and adapted to catch auxiliary yarn and to release the same when the movable means is moved, means to cause auxiliary yarn to be caught by said auxiliary-yarn feeding means at one or more desired points in the operation of the machine, means to cause said movable means to be moved at one or more points each spaced a limited distance along said bed from the point where a yarn is adapted to be caught by said auxiliary-yarn feeding means so as to release said yarn, and means to cause said needles to embody said yarns in a fabric.

2. A knitting machine comprising a needle bed, operating means, said bed and said operating means being mounted for relative movement, a series of needles on said bed, means forming part of said operating means to feed primary yarn

into position to be received by said needles, auxiliary-yarn feeding means forming part of said operating means and adapted to catch auxiliary yarn and to release the same, means to cause auxiliary yarn to be caught by said auxiliary-yarn feeding means at one or more desired points in the operation of the machine, positive means to cause yarn to be released from said auxiliary-yarn feeding means at one or more successive points in the operation of the machine, the last-mentioned causing means being so mounted that it may be disposed in various positions for determining the point of effectiveness thereof to vary the interval between the catching and releasing of the yarn by said auxiliary-yarn feeding means, and means to cause said needles to embody said yarns in the fabric.

3. A knitting machine comprising a needle bed, operating means, said bed and said operating means being mounted for relative movement, a series of needles on said bed, a plurality of primary-yarn feeding means forming a part of said operating means, a plurality of auxiliary-yarn feeding means forming part of said operating means and adapted to catch auxiliary yarn, means to position auxiliary yarn to be caught by said auxiliary-yarn feeding means at desired points in the operation of the machine, means independent of said positioning means to cause yarn caught by yarn-feeding means to be released therefrom at a given point after the yarn has been fed into position to be received by a limited number of said needles, and means forming part of said operating means to cause said needles to embody said yarns in a fabric.

4. A circular knitting machine comprising a needle bed, operating means, said bed and said operating means being mounted for relative rotative movement, a series of needles on said bed, a plurality of primary-yarn feeding means forming a part of said operating means, a plurality of auxiliary-yarn feeding means forming part of said operating means and adapted to catch auxiliary yarn and to feed it into position to be received by certain of said needles, adjustable means to position auxiliary yarn to be caught by said auxiliary-yarn feeding means, means operative from time to time during the operation of said machine to selectively control the adjustment of said positioning means, means independent of the positioning means to cause yarn to be released from an auxiliary-yarn feeding means after the same has fed said yarn for a portion of a revolution, and means forming part of said operating means to cause said needles to embody said yarns in a fabric.

5. A knitting machine comprising a needle bed, operating means, said bed and said operating means being mounted for relative movement, a series of needles on said bed, means forming part of said operating means to feed primary yarn into position to be received by said needles, auxiliary-yarn feeding means forming part of said operating means and adapted to catch auxiliary yarn and to release the same, means to cause any desired one of a plurality of auxiliary yarns to be caught by said auxiliary-yarn feeding means at a desired point in the operation of the machine, means independent of said causing means to cause yarn caught by said auxiliary-yarn feeding means to be released at a subsequent point in the same course, and means to actuate said needles.

6. A knitting machine comprising a needle bed, operating means, said bed and said operating means being mounted for relative movement, a

- series of needles on said bed, means forming part of said operating means to feed primary yarn into position to be received by said needles, auxiliary-yarn feeding means forming part of said operating means and adapted to catch auxiliary yarn, means to position auxiliary yarn to be caught by said auxiliary-yarn feeding means at one or more desired points in the operation of the machine, and means to cause yarn to be released from said auxiliary-yarn feeding means in the same course of knitting in which yarn is caught regardless of the position of the positioning means.
7. A knitting machine comprising a needle bed, operating means, said bed and said operating means being mounted for relative movement, a series of needles on said bed, means forming part of said operating means to feed primary yarn into position to be received by said needles, auxiliary-yarn feeding means forming part of said operating means and adapted to catch auxiliary yarn, means to position auxiliary yarn to be caught by said auxiliary-yarn feeding means at desired stages in the operation of the machine, means associated with said bed to cause release of yarn from said auxiliary-yarn feeding means at desired points in the operation of the machine regardless of the position of the positioning means, and means to cause said needles to embody said yarns in a fabric.
8. A circular knitting machine comprising a needle bed, operating means, said bed and said operating means being mounted for relative rotation, a series of needles on said bed, means forming part of said operating means to feed primary yarn into position to be received by said needles, auxiliary-yarn feeding means forming part of said operating means and adapted to catch auxiliary yarn and to release the same, means to position auxiliary yarn to be caught by said auxiliary-yarn feeding means at a plurality of points about the machine, selective means for operating said positioning means, releasing means operative upon said auxiliary-yarn feeding means at a plurality of points about the machine, and means to cause said needles to embody said yarns in the fabric.
9. A knitting machine comprising a needle bed, operating means, said bed and said operating means being mounted for relative movement, a series of needles on said bed, means forming a part of said operating means to feed primary yarn into position to be received by said needles, supplemental means also forming a part of said operating means to catch auxiliary yarn and to feed the same into position to be received by said needles, means to cause auxiliary yarn to be caught by said supplemental means at a multiplicity of points along said bed, independent means to cause yarn to be released from said supplemental means at points intermediate successive points at which it is caught, and means to actuate said needles.
10. A circular knitting machine comprising a stationary needle cylinder, a series of needles on said cylinder, means adapted to revolve about said cylinder to feed primary yarn into position to be received by said needles, supplemental-yarn feeding means adapted to revolve about said cylinder and to catch auxiliary yarn and to release the same after the supplemental means has traveled a portion of a revolution, means to position auxiliary yarn to be caught by said supplemental means at one or more desired points about said cylinder, means independent of said positioning means to cause said supplemental
- means to release yarn caught thereby at one or more desired points about said cylinder, and means to actuate said needles.
11. A knitting machine comprising a needle bed, operating means, said bed and said operating means being mounted for relative movement, a series of needles on said bed, means forming a part of said operating means to feed primary yarn into position to be received by said needles, means also forming a part of said operating means to catch and to feed to certain of said needles auxiliary yarn when the latter is positioned to be caught thereby, means to position auxiliary yarn to be caught by said catching and feeding means at desired points in the operation of the machine, and means to actuate said needles in such a manner that one or more of said certain of said needles will knit auxiliary yarn in certain courses and that those needles will not knit primary yarn in the courses in which they knit auxiliary yarn.
12. A knitting machine comprising a needle bed, operating means, said bed and said operating means being mounted for relative movement, a series of needles on said bed, means forming a part of said operating means to feed primary yarn into position to be received by said needles, means also forming a part of said operating means to feed auxiliary yarn into position to be received by a group of said needles, and means to cause said auxiliary yarn to be caught into the fabric by a plurality of the needles of said group in a manner that involves the knitting of only one of said yarns on a single needle in any one course and in such a manner that the auxiliary yarn appears primarily at least on the back of the fabric.
13. A knitting machine comprising a needle bed, operating means, said bed and said operating means being mounted for relative movement, a series of needles on said bed, means forming a part of said operating means to feed primary yarn into position to be received by said needles, means also forming part of said operating means for feeding an auxiliary yarn into position to be received by a group of said needles, for causing a plurality of successive needles of said group to knit said auxiliary yarn, and for causing certain of the latter needles to receive an adjacent portion of said auxiliary yarn in the same course without knitting; and means to cause needles other than those which knit auxiliary yarn to knit primary yarn.
14. A knitting machine comprising a bed, operating means, said bed and said operating means being mounted for relative movement, a series of needles on said bed, yarn feeding means forming part of said operating means and adapted to catch a yarn and to release it at successive points in said relative movement, means to supply a yarn to be caught by said yarn feeding means, means to cause a group of said needles to receive yarn after it is caught by said yarn feeding means and to knit said yarn, means to position certain of said group of needles for the reception of an adjacent portion of said yarn without knitting, and means operative after the release of said yarn by said yarn feeding means to cause certain of said group of needles to again receive said yarn before knitting.
15. A knitting machine comprising a bed, a group of needles on said bed, means disposed adjacent to a given point on said bed to deliver yarn to be fed to said needles, means to feed said yarn to said needles, means to cause said needles

- to knit said yarn, said feeding means being operative to release said yarn so that it will extend substantially directly to said delivery means from the last needle by which it was knitted pursuant to the operation of the last mentioned means, means to position at least certain of said needles for the reception of yarn so extending from the last needle, and means to cause said such yarn to be embodied in the fabric.
- 10 16. A knitting machine comprising a bed, a group of needles on said bed, means disposed adjacent to a given point on said bed to deliver yarn to be fed to said needles, means to feed said yarn to said needles, means to cause said needles to knit said yarn, means to position certain of said needles for the reception of yarn without knitting, means to cause said yarn to be released from said feeding means so that it will extend substantially directly from the last needle by which it is knitted to said delivery means and to cause it to be positioned for reception by said certain of said needles, so that the yarn extending toward the delivery means from said last needle will be caught into the fabric.
- 15 17. A knitting machine comprising a needle bed, operating means, said bed and said operating means being mounted for relative movement, a series of needles on said bed, a plurality of yarn feeding means forming a part of said operating means, certain of said yarn feeding means being adapted to feed primary yarn into position to be received by said needles and other of said yarn-feeding means being adapted to feed auxiliary yarn into position to be received by only one or more groups of said needles, and needle actuating units individually associated with individual ones of said yarn feeding means, said yarn feeding means being removably and replaceably mounted so that either type of yarn feeding means may be associated with a given actuating unit as desired.
- 20 18. A knitting machine comprising a needle bed, operating means, said bed and said operating means being mounted for relative movement, a series of needles on said bed, a plurality of yarn feeding means forming a part of said operating means, certain of said yarn feeding means being adapted to feed primary yarn into position to be received by said needles and other of said yarn feeding means being adapted to feed auxiliary yarn into position to be received by only one or more groups of said needles, and needle actuating units associated with each of said yarn feeding means, said units being of similar character to permit any desired type of yarn feed to be utilized with any one of the same.
- 25 19. A knitting machine comprising a needle bed, operating means, said bed and said operating means being mounted for relative movement, a series of needles on said bed, means forming part of said operating means to feed primary yarn into position to be received by said needles, auxiliary-yarn feeding means forming part of said operating means and adapted to catch auxiliary yarn and to release the same, means to cause auxiliary yarn to be caught by said auxiliary-yarn feeding means at one or more desired points in the operation of the machine, a sinker bed, means mounted on said sinker bed to cause said auxiliary-yarn feeding means to release yarn at desired points in the operation of the machine, and means to cause said needles to embody said yarns in a fabric.
- 30 20. A knitting machine comprising a circular needle bed, actuator mechanism, circular mounting means for said actuator mechanism, said bed and said mounting means being mounted for relative rotative movement, supporting means connected with said mounting means, carrier means freely supported on said supporting means, means to cause relative rotation between said carrier means and said supporting means so that said bed and said carrier means may be maintained substantially immovable with respect to each other, and yarn-supplying means carried by said carrier means.
- 35 21. A circular knitting machine comprising a needle cylinder, a series of needles on said cylinder, operating means including elevated means to supply yarn for said needles, said cylinder and said operating means being mounted for relative rotation, an interior member supported from said operating means; and gear means including a portion carried by said operating means, an exterior portion, and a portion carried by said interior member, and adapted to cause relative rotation between said operating means and said interior member.
- 40 22. A circular knitting machine comprising a needle cylinder, a series of needles on said cylinder, operating means, said cylinder and said operating means being mounted for relative rotation, an interior member supported from said operating means; gear means including a portion carried by said operating means, an exterior portion, and a portion carried by said interior member; means forming a part of said operating means to feed primary yarn into position to be received by said needles, means also forming a part of said operating means to feed auxiliary yarn into position to be received by spaced successions of said needles, and means carried by said interior member to supply yarn to said auxiliary-yarn feeding means for feeding to said successions of needles, said gear means serving to hold the interior member in such relative position to said cylinder that an auxiliary yarn may be supplied to said auxiliary-yarn feeding means for feeding to each succession of needles.
- 45 23. A knitting machine comprising a needle bed, operating means, said bed and said operating means being mounted for relative movement, a series of needles on said bed, means forming a part of said operating means to feed primary yarn into position to be received by said needles, means also forming part of said operating means for feeding auxiliary yarn into position to be received by only one or more groups of said needles but not by others of said needles, means for causing at least certain of the needles of said group or groups to knit auxiliary yarn in certain portions of the fabric, and means for causing primary yarn to be knit in other portions of said fabric and to be caught into the fabric in said certain portions thereof.
- 50 24. A knitting machine comprising a needle bed, operating means, said bed and said operating means being mounted for relative movement, a series of needles on said bed, means forming part of said operating means to feed primary yarn to said needles, means to cause auxiliary yarn to extend laterally of said needle bed, means forming part of said operating means to dispose said laterally extending yarn in a given position relatively to said bed to effectuate its proper reception by needles at a portion of said bed and to feed said auxiliary yarn to certain of said needles in such position, and means independent of said causing means to assure that said dis-
- 55 75

posing and feeding means will not dispose yarn for reception by needles located beyond said portion.

25. A yarn feed for a knitting machine comprising a member having a sloping forward surface adapted when a laterally extending yarn is intercepted thereby to move said yarn in a direction transverse to the direction in which the yarn extends so as to dispose the yarn in a desired 10 position for reception by the needles of the machine, said member having means located rearwardly of said sloping surface to catch the yarn when so disposed by said surface and to feed the yarn to certain of said needles.

15. 26. A knitting machine comprising a needle bed, a series of needles on said bed, means to dispose yarn for reception by yarn feeding means at a plurality of points about the machine, and means to cause a group of said needles to knit 20 the yarn so disposed at one point and another group of needles to knit yarn so disposed at another point but not to knit or catch into the fabric yarn knitted by any other needles than those of the group in question, the last mentioned means including yarn feeding means 25 adapted to catch yarn so disposed by the first mentioned means.

27. A circular knitting machine comprising a needle bed, needles on said bed, a plurality of 30 yarn-guiding means individually arranged to supply yarn to be fed to individual groups of said needles, yarn-feeding means arranged to feed yarn from individual yarn-guiding means into position for needle reception, means including 35 yarn-releasing means to prevent yarn fed by said yarn-feeding means to one group of needles from being received by needles of any other of said groups, said bed and said yarn-feeding means being mounted for relative rotation on the axis of said bed, and means to cause needles 40 of said individual groups to be operated during a plurality of successive relative rotations to receive yarn only from the aforesaid yarn-feeding means.

45. 28. A circular knitting machine comprising a needle bed, needles on said bed, a plurality of yarn-guiding means individually arranged to supply yarn to be fed to individual groups of said needles, yarn-feeding means arranged to feed 50 yarn from individual yarn-guiding means into position for needle reception, means including yarn-releasing means to prevent yarn fed by said yarn-feeding means to one group of needles from being received by needles of any other of said groups, said bed and said yarn-feeding means 55 being mounted for relative rotation on the axis of said bed, said machine being so arranged that yarn will be received by the needles only from the aforesaid yarn-feeding means during a multiplicity of successive relative rotations.

60. 29. The method of forming separate strips of knitted fabric by the manipulation of needles on a circular knitting bed, which comprises supplying individual yarns at a series of points disposed 65 in a fixed circumferential relation to said bed and causing each of said yarns to be drawn out past needles of individual groups, and causing needles of said individual groups to receive and manipulate only yarn drawn out from individual 70 ones of said points.

75. 30. A knitting machine comprising a needle bed, operating means, said bed and said operating means being mounted for relative movement, a series of needles on said bed, means forming part of said operating means to feed primary

yarn into position to be received by said needles, means also forming part of said operating means to feed auxiliary yarn into position to be received by a group of said needles, and means to cause said auxiliary yarn to be caught by a plurality of 5 the needles of said group into the fabric at certain portions thereof without knitting.

31. A circular knitting machine comprising a bed, needles on said bed, needle actuating means, said actuating means and said bed being mounted 10 for relative rotation in a given direction, means to cause yarn to extend in the direction of rotation in position to be received by a group of said needles, said actuating means being adapted to position at least certain of the needles of said group for the reception of yarn so extended, means thereafter to cause yarn to extend in a generally opposite direction from the last needle by which it was previously received and in position to be received by at least certain of the 20 needles of said group, said actuating means being arranged to position at least certain of the needles of said group for the reception of yarn so extending, and means to cause said yarn to be 25 embodied in a fabric.

32. A knitting machine comprising a needle bed, needles on said bed, yarn-feeding means adapted to catch suitably disposed yarn and to feed it into position for reception by certain of said needles, a sinker bed, and means to cause 30 the release at a given point of the yarn caught by the yarn-feeding means, said release-causing means comprising means carried by said sinker bed.

35. A knitting machine comprising a needle bed and a sinker bed, operating means, said beds and said operating means being mounted for relative movement, needles on said bed, yarn-feeding means forming part of said operating means and adapted to catch suitably disposed 40 yarn, and means to cause the release of yarn caught by the yarn-feeding means, said sinker bed being formed with slots and said release-causing means comprising means removably disposed in certain of said slots.

45. 34. A knitting machine comprising a needle bed, needles on said bed, means to hold yarn in position to be caught by yarn-feeding means, yarn-feeding means adapted to catch yarn held by said holding means, and means independent 50 of said holding means to cause said yarn to be released from said yarn-feeding means after the yarn has been fed into position to be received by a limited number of said needles.

55. 35. A circular knitting machine comprising a needle bed, operating means, said bed and said operating means being mounted for relative rotation, needles on said bed, means forming part of said operating means for feeding primary yarn into position to be received by 60 said needles, auxiliary-yarn feeding means also forming part of said operating means, and adapted to catch suitably positioned auxiliary yarn and to feed said yarn into position to be received by needles until said yarn is released, means to 65 hold auxiliary yarn in position to be caught by said auxiliary-yarn feeding means, means independent of said holding means to cause yarn caught by said auxiliary-yarn feeding means to be released at the end of an arc of a desired 70 extent, and means to operate said needles to suitably embody said yarns into a fabric.

75. 36. A knitting machine comprising a needle bed, operating mechanism, said bed and said operating mechanism being mounted for relative 75

movement, needles on said bed, a yarn-guide disposed at a given point along said bed and adapted to dispose yarn in position to be caught by a part of said operating mechanism, and means forming part of said operating mechanism and adapted to catch a yarn from said yarn-guide when a yarn is so disposed by the yarn guide and to cause the yarn to be drawn out from said yarn guide past a predetermined portion of said bed and to be released at a given point marking the end of said portion, said means acting to cause the yarn to be drawn out and to be released regardless of the position of the yarn guide at the times of the drawing-out and the releasing actions.

37. A knitting machine comprising a needle bed, operating mechanism, said bed and said operating mechanism being mounted for relative movement, needles on said bed, a yarn-guide disposed at a given point along said bed and adapted to dispose yarn in position to be caught by a part of said operating mechanism, means forming part of said operating mechanism and adapted to catch a yarn from said yarn-guide when a yarn is so disposed by the yarn-guide and to cause the yarn to be drawn out from said yarn guide past a predetermined portion of said bed and to be released at a given point marking the end of said portion, said means acting to cause the yarn to be drawn out and to be released regardless of the position of the yarn guide at the times of the drawing-out and the releasing actions, and means to maintain said yarn substantially taut at all times.

38. A circular knitting machine comprising a needle bed, needles on said bed, means to deliver yarn at a given plane which extends generally transversely to said bed, means to catch and draw out yarn from said delivery means and to feed said yarn into position to be received by at least certain of a group of said needles, the last-mentioned means comprising an element adapted to be moved to release the yarn caught thereby, and means to move said element to release the yarn after a desired amount thereof, which is only sufficient to be incorporated in less than a circular course, has been drawn out.

39. In a knitting machine, yarn-feeding means comprising an element adapted to catch yarn and to be moved to cause yarn caught thereby to be released, means to so move said element, and means to immediately restore said element to a yarn catching position.

40. A knitting machine comprising a needle bed, needles on said bed, means to deliver yarn at a given plane which extends generally transversely to said bed, means to draw out said yarn from said plane and to feed it into position to be received by at least certain of a group of said needles, means to cause yarn to be released from said feeding means, and means to cause a portion of said yarn between the last needle by which the yarn was caught and said delivery means to be received by one or more of the needles of said group before additional yarn is drawn out from said delivery means.

41. A knitting machine comprising a rotating portion and a non-rotating portion, a bed forming part of one of said portions, a series of needles on said bed, means forming part of said one of said portions to hold a yarn in position to be intercepted by feeding means, means forming part of the other of said portions to intercept a yarn so held and to feed it into position to be received only by a limited number of needles,

means independent of said holding means to cause said yarn to be released when said feeding means is adjacent a given point on said bed, and selective means to cause certain of said limited number of needles to receive yarn positioned by said feeding means.

42. A knitting machine comprising a series of needles, means to feed yarn into position to be received by all the needles of said series, means to feed a striping yarn into position to be received by a group of said needles but not by the others thereof, means to select certain of the needles of said group and to advance the same and to retract the same to knit said striping yarn, and means to advance certain other needles of said series and to retract the same to knit loops of said first-mentioned yarn and to select spaced one of said certain of said needles and to cause the same to embody said first-mentioned yarn in the fabric without knitting. 20

43. A circular knitting machine comprising a non-rotating needle bed, rotating means including means for feeding yarn to said needles, means extending outside of said bed to support said rotating means, means supported by said rotating means and including at least a portion disposed internally of a portion of said rotating means, a generally annular element, external means acting at least during the greater part of the operation of the machine to hold said annular means against rotation with said rotating means, and means to substantially prevent said portion-including means from rotating with said rotating means, said rotation-preventing means including means forming a part of said rotating means and contacting with a surface of said portion-including means and being independently rotatable during the rotation of the rotating means. 30

44. A circular knitting machine comprising a non-rotating needle bed, rotating means including means for feeding yarn to said needles, means extending outside of said bed to support said rotating means, means supported by said rotating means and including at least a portion disposed internally of a portion of said rotating means, a generally annular element, external means acting at least during the greater part of the operation of the machine to hold said element means against rotation with said rotating means, means to substantially prevent said portion-including means from rotating with said rotating means, said rotation-preventing means including means forming a part of said rotating means and contacting with a surface of said annular means and a surface of said portion-including means and being independently rotatable during the rotation of the rotating means, and means for adjusting the relative circumferential position of said bed and said portion-including means. 50

45. A knitting machine comprising a circular needle bed, actuator mechanism, circular mounting means for said actuator mechanism, said bed and said mounting means being mounted for relative movement, supporting means associated with said mounting means, internal means freely supported on said supporting means, and means to cause relative rotation between said internal means and said supporting means so that said bed and said internal means may be maintained substantially immovable with respect to each other, said causing means being oriented and arranged so as not to contact with tubular fabric formed on said machine. 60

46. A knitting machine comprising a circular 75

- needle bed, actuator mechanism, circular mounting means for said actuator mechanism, said bed and said mounting means being mounted for relative movement, supporting means associated with said mounting means, internal means freely supported on said supporting means, means to cause relative rotation between said internal means and said supporting means so that said bed and said internal means may be maintained substantially immovable with respect to each other, said causing means being adapted and arranged so as not to contact with tubular fabric formed on said machine, and means to adjust the relative circumferential position of said internal means and said bed.
47. A knitting machine comprising a circular needle bed, actuator mechanism, circular mounting means for said actuator mechanism, said bed and said mounting means being mounted for relative rotative movement, supporting means connected with said mounting means, a needle dial freely supported on said supporting means, and means to cause relative rotation between said needle dial and said supporting means so that said bed and said needle dial may be maintained substantially immovable with respect to each other.
48. A knitting machine comprising a needle bed, operating means, said bed and said operating means being mounted for relative movement, a series of needles on said bed, a plurality of yarn-feeding means forming part of said holding means and adapted to catch suitably disposed yarn and to feed it into position for reception by certain of said needles, means to position yarn to be caught by said yarn-feeding means during said relative movement, means operative in the same course of knitting in which yarn is caught to cause yarn to be released from one of said yarn-feeding means at a given point but not from another of said yarn-feeding means at said point, means to cause yarn to be released from said other of said yarn-feeding means at another point but not from said one of said yarn-feeding means at said other point, and means to selectively manipulate said needles for the reception of said yarn from said yarn-feeding means.
49. A knitting machine comprising a needle bed, operating means, said bed and said operating means being mounted for relative movement, a series of needles on said bed, a plurality of yarn-feeding means forming part of said holding means and adapted to catch suitably disposed yarn and to feed it into position for reception by certain of said needles, selective means to position yarn to be caught by said yarn-feeding means during said relative movement, means operative in the same course of knitting in which yarn is caught to cause yarn to be released from one of said yarn-feeding means at a given point but not from another of said yarn-feeding means at said point, means to cause yarn to be released from said other of said yarn-feeding means at another point but not from said one of said yarn-feeding means at said other point, and means to selectively manipulate said needles for the reception of yarn from said yarn-feeding means.
50. A knitting machine comprising a needle bed, a series of needles on said bed, a plurality of yarn guides individually disposed at points to one side of the edge line of each group of a plurality of successive groups of said needles, means to draw out yarn from said yarn guides and to dispose them in position to be received by certain of said needles, means to manipulate said needles, and means including said drawing-out means and said manipulating means to cause yarn from one yarn guide to be received by certain of the needles of one group and at least one of the needles of an adjacent group in one course and yarn from another of said yarn guides to be received by certain of the needles of said adjacent group in said course but not by the needles of said one group in said course and to cause yarn from said other of said yarn guides to be received by certain of the needles of said adjacent group and by at least one of the needles of said one of said groups in a successive course and yarn from said one of said yarn guides to be received by certain of the needles of said one of said groups in said successive course but not by the needles of said adjacent group in said successive course.
51. A circular knitting machine comprising a needle bed, operating means, said bed and said operating means being mounted for relative rotative movement, needles on said bed, yarn-feeding means forming part of said operating means and adapted to catch suitably positioned yarn and to feed said yarn into position to be received by the needles until said yarn is released, means to hold yarn in position to be caught by said yarn-feeding means, means independent of said holding means to cause yarn caught by said yarn-feeding means to be released at the end of an arc of a desired extent, and means to operate said needles to suitably manipulate said yarn.
52. A circular knitting machine comprising a needle bed, operating means, said bed and said operating means being mounted for relative rotative movement, needles on said bed, yarn-feeding means forming part of said operating means and adapted to catch suitably positioned yarn and to feed said yarn into position to be received by the needles until said yarn is released, means to hold yarn in position to be caught by said yarn-feeding means, means independent of said holding means to cause yarn caught by said yarn-feeding means to be released at the end of an arc of a desired extent, means to determine the extent of said arc, and means to operate said needles to suitably manipulate said yarn.
53. A circular knitting machine comprising a needle bed, operating means, said bed and said operating means being mounted for relative rotative movement, needles on said bed, yarn-feeding means forming part of said operating means and adapted to catch suitably positioned yarn and to feed said yarn into position to be received by the needles until said yarn is released, means to hold yarn in position to be caught by said yarn-feeding means, means independent of said holding means to cause yarn caught by said yarn-feeding means to be released at the end of an arc of a desired extent, said causing means including means so mounted that it may be disposed in various positions for determining the extent of said arc, and means to operate said needles to suitably manipulate said yarn.
54. A circular knitting machine comprising a needle bed, operating means, said bed and said operating means being mounted for relative rotative movement, a series of needles on said bed, a yarn guide disposed adjacent to a point on said bed, means which includes means for drawing out yarn from said yarn guide and which is constructed and arranged to cause a portion of said

- yarn extending in one direction to be received by at least certain of a group of said needles and thereafter to cause a portion of said yarn extending in a generally opposite direction to be received by at least certain of the needles of said group, and means to selectively manipulate the needles of said group to incorporate said yarn into a fabric.
55. A knitting machine comprising a needle bed, needles on said bed, means to deliver yarn at a given plane which extends generally transversely to said bed, means to draw out said yarn from said plane and to feed it into position to be received by at least two of a group of said needles, and means to cause a portion of said yarn between the last needle by which the yarn was received and said delivery means to be received by at least one of the needles of said group intermediate the first and last needles by which the yarn was primarily received and in such manner that said portion of the yarn will extend in a reverse direction to the direction in which the yarn extended when received by said first and last needle.
56. A knitting machine comprising a needle bed, operating means, said bed and said operating means being mounted for relative movement, a series of needles on said bed, means forming part of said operating means to feed primary yarn into position to be received by said needles, auxiliary-yarn feeding means forming part of said operating means and adapted to catch auxiliary yarn, adjustable means to position auxiliary yarn to be caught by said auxiliary-yarn feeding means at one or more desired points in the operation of the machine, means to cause yarn to be released from said auxiliary-yarn feeding means in the same course of knitting in which it is caught, and means to selectively control the adjustment of said positioning means to determine when a given auxiliary yarn will be so positioned as to be caught, said causing means being operative regardless of the position of the positioning means.
57. A circular knitting machine comprising a needle bed, a series of needles on said bed, yarn-feeding means, said bed and said yarn-feeding means being mounted for relative rotation, said yarn-feeding means including means to feed primary yarn into position to be received by said needles and supplemental means adapted to catch auxiliary yarn and to feed it into position to be received by a limited number of said needles, means to position auxiliary yarn to be caught by said supplemental means at one or more desired points about said bed, means independent of said positioning means to cause yarn caught by said supplemental means to be released after a portion of a rotation, and means to actuate said needles.
58. A knitting machine comprising a needle bed, operating means, said bed and said operating means being mounted for relative movement, a series of needles on said bed, means forming a part of said operating means to feed primary yarn into position to be received by said needles, means also forming part of said operating means for feeding an auxiliary yarn into position to be received by a group of said needles, for causing a plurality of successive needles of said group to knit said auxiliary yarn, and for causing certain of the latter needles to receive an adjacent portion of said auxiliary yarn without knitting, and means to cause only needles other than those which knit auxiliary yarn to knit primary yarn.
59. A circular knitting machine comprising a needle bed, a series of needles on said bed, means to cause a portion of a strand of yarn to be received by at least certain of a group of said needles while extending in one direction and thereafter in the same rotation to cause an adjacent portion of said strand to be received by at least certain of the needles of said group while extending in a generally opposite direction and to incorporate said portions into the fabric, the last-mentioned means including means to selectively manipulate the needles of said group, and said manipulating means and said bed being mounted for relative rotation in a single direction only.

VINCENT LOMBARDI.

Patent No. 2,130,769.

September 20, 1938.

VINCENT LOMBARDI.

It is hereby certified that error appears in the printed specification of the above numbered patent requiring correction as follows: Page 12, first column, line 8, claim 15, strike out the word "said"; page 14, first column, line 8, claim 36, for "to the cause" read to cause; and second column, line 18, claim 42, for "one" read ones; page 15, first column, line 46, claim 48, strike out the word "said" first occurrence; and that the said Letters Patent should be read with this correction therein that the same may conform to the record of the case in the Patent Office.

Signed and sealed this 10th day of January, A. D. 1939.

Henry Van Arsdale

- yarn extending in one direction to be received by at least certain of a group of said needles and thereafter to cause a portion of said yarn extending in a generally opposite direction to be received by at least certain of the needles of said group, and means to selectively manipulate the needles of said group to incorporate said yarn into a fabric.
55. A knitting machine comprising a needle bed, needles on said bed, means to deliver yarn at a given plane which extends generally transversely to said bed, means to draw out said yarn from said plane and to feed it into position to be received by at least two of a group of said needles, and means to cause a portion of said yarn between the last needle by which the yarn was received and said delivery means to be received by at least one of the needles of said group intermediate the first and last needles by which the yarn was primarily received and in such manner that said portion of the yarn will extend in a reverse direction to the direction in which the yarn extended when received by said first and last needle.
56. A knitting machine comprising a needle bed, operating means, said bed and said operating means being mounted for relative movement, a series of needles on said bed, means forming part of said operating means to feed primary yarn into position to be received by said needles, auxiliary-yarn feeding means forming part of said operating means and adapted to catch auxiliary yarn, adjustable means to position auxiliary yarn to be caught by said auxiliary-yarn feeding means at one or more desired points in the operation of the machine, means to cause yarn to be released from said auxiliary-yarn feeding means in the same course of knitting in which it is caught, and means to selectively control the adjustment of said positioning means to determine when a given auxiliary yarn will be so positioned as to be caught, said causing means being operative regardless of the position of the positioning means.
57. A circular knitting machine comprising a needle bed, a series of needles on said bed, yarn-feeding means, said bed and said yarn-feeding means being mounted for relative rotation, said yarn-feeding means including means to feed primary yarn into position to be received by said needles and supplemental means adapted to catch auxiliary yarn and to feed it into position to be received by a limited number of said needles, means to position auxiliary yarn to be caught by said supplemental means at one or more desired points about said bed, means independent of said positioning means to cause yarn caught by said supplemental means to be released after a portion of a rotation, and means to actuate said needles.
58. A knitting machine comprising a needle bed, operating means, said bed and said operating means being mounted for relative movement, a series of needles on said bed, means forming a part of said operating means to feed primary yarn into position to be received by said needles, means also forming part of said operating means for feeding an auxiliary yarn into position to be received by a group of said needles, for causing a plurality of successive needles of said group to knit said auxiliary yarn, and for causing certain of the latter needles to receive an adjacent portion of said auxiliary yarn without knitting, and means to cause only needles other than those which knit auxiliary yarn to knit primary yarn.
59. A circular knitting machine comprising a needle bed, a series of needles on said bed, means to cause a portion of a strand of yarn to be received by at least certain of a group of said needles while extending in one direction and thereafter in the same rotation to cause an adjacent portion of said strand to be received by at least certain of the needles of said group while extending in a generally opposite direction and to incorporate said portions into the fabric, the last-mentioned means including means to selectively manipulate the needles of said group, and said manipulating means and said bed being mounted for relative rotation in a single direction only.
